UNITED STATES PATENT OFFICE.

FRANCIS A. COFFIN, OF INDIANAPOLIS, INDIANA.

DESIGN FOR A DRAWER-PULL.

SPECIFICATION forming part of Design No. 18,978, dated April 2, 1889.

Application filed January 24, 1889. Serial No. 297,443. Term of patent 7 years.

To all whom it may concern:

Be it known that I, FRANCIS A. COFFIN, of Indianapolis, county of Marion, and State of Indiana, have invented and produced a certain new and original Design for a Drawer-Pull; and I do hereby declare that the following is a full, clear, and exact description thereof, reference being had to the accompanying drawings, in which like letters refer to like parts.

My invention consists in a new and original design for drawer-pulls, and will be understood from the following description.

In the drawings, Figure 1 is a perspective view of my design. Fig. 2 is a cross-section through the center thereof.

The design will be brought out more perfectly when the color of the drawer-pull harmonizes with that of the desk or article of furniture to which it is attached, and the proportions are preferably those shown in the drawings. The base is rounded upon the

front and ends, as indicated at *r* and *e*, and is surmounted by a top piece or plain bead marked *b*, whose front and back are parallel and the top slightly beveled, as shown in Fig. 2. The central part of the back is hollowed out to form a grip, *g*, as shown in Fig. 2. The leading feature of my design is the body portion with rounded front and ends and surmounted by a top piece, *b*, the line of the back and the bottom part of the drawer-pull being about at right angles to each other.

I claim—

As a design, the drawer-pull having a body portion formed with convex rounded ends and front surmounted by a top part or projection, *b*, substantially as shown and described.

In witness whereof I have hereunto set my hand this 19th day of January, 1889.

FRANCIS A. COFFIN.
